UNITED STATES PATENT OFFICE.

JOHN GEORGE MENGEL, JR., OF BALTIMORE, MARYLAND.

DESIGN FOR A FONT OF PRINTING-TYPE.

SPECIFICATION forming part of Design No. 15,724, dated January 13, 1885.

Application filed November 25, 1884. Term of patent 7 years.

To all whom it may concern:

Be it known that I, JOHN G. MENGEL, Jr., of the city of Baltimore, in the State of Maryland, have invented and produced a new and 5 original Design for a Font of Printing-Type, of which the following is a specification, reference being had to the accompanying typographical impression, making a part thereof.

This font is designed for the printing of ornamental head-lines, names, titles, &c., and not for general printing, and it does not comprise the lower-case letters, but includes, beside the capital letters, numerals, punctuation-marks, and ornamental types, as hereinafter 10 specified. In this font all of the letters, &c., are of regular shape, and are of a width almost equal to their height. All the lines which compose the letters are full lines of nearly uniform appearance, very little shading being 15 given to the letters. Each of the letters B, D, E, F, H, I, J, K, L, M, N, P, R, T, U, V, W, X, Y, and Z has a small downwardly-curving tongue extending out from the left-hand side

about the center of the letter. The letter A has a cap similar to that of a capital T. 25

In addition to the usual letters, numerals, and punctuation-marks, the font comprises vertical types, both light and heavy, which are placed after each letter in setting up a word; upper and lower borders, as shown, 30 which are placed above and below words, &c.; one initial and two terminal types to be placed before and after each head-line, name, title, &c., and two rosette-types, which are placed between the words constituting a head-line, 35 name, title, &c.

I claim as my invention—

The design for a font of printing-type, substantially as shown and described.

In testimony whereof I affix my signature in 40 presence of two witnesses.

JOHN GEORGE MENGEL, JR.
